UNITED STATES PATENT OFFICE.

OLOF EMANUEL MYREN JOHNSON, OF NEWETT, COLORADO.

HATCHET.

1,142,101.

Specification of Letters Patent.

Patented June 8, 1915.

Application filed August 21, 1911. Serial No. 645,235.

To all whom it may concern:

Be it known that I, OLOF EMANUEL MYREN JOHNSON, a citizen of Sweden, residing at Newett, in the county of Chaffee and State of Colorado, have invented certain new and useful Improvements in Hatchets, of which the following is a specification.

This invention relates to improvements in hatchets and its object is to produce a tool of this class having a detachable blade secured to the head so that should the blade be broken or damaged in usage it may be replaced with a new one without destroying the utility of the tool.

Other objects are to produce a tool of this character that is simple and inexpensive to manufacture, efficient and durable.

With the foregoing and other objects in view the invention consists in the combination and arrangement of parts to be herein-after more fully described in the following specification, pointed out in the claim and illustrated in the accompanying drawing which forms a part of the said specification and in which—

Figure 1 is a side elevation of the tool showing the handle partly broken away and the blade retaining mechanism in dotted lines. Fig. 2 is an elevation of the head of the tool, partly in section, showing the blade retaining mechanism. Fig. 3 is an end view. Fig. 4 is an inverted plan of a portion of Fig. 3.

Like reference characters indicate corresponding parts throughout the several views.

1 is the hatchet handle of ordinary construction and provided with a head 2 formed without the usual integral cutting blade but with means for retaining my removable blade. At the forward end of the head 2 its solid body portion is terminated at 6 but the lateral walls are projected beyond this line and turned inwardly toward each other to form oppositely disposed dovetails 3 and 4 and a space is formed between the said dovetails and between the line 6 and the dovetails. The latter cavity is terminated by a shoulder 7 which is projected from the head 2 to meet the dovetail continuations at 5 which latter members extend

from the upper to the lower edge of the head 2 or its entire depth.

8 is the detachable blade having a cutting edge 9 and a neck 10 projected beyond its rear termination and ending in a head 11. Within this head is formed a rectangular recess 12 in which is secured a lever 13, by a pivot 14 fastened in the head 11, having its upper end beveled as shown.

15 is a spring secured in the recessed head 11 having its opposite end fixed in a recess 16 in the lever 13 for the purpose of drawing the lever toward the said head. A lug 17 secured to the lever 13 is adapted to enter a recess 18 in the head 2. Lying loosely within the recess 12 of the head 11 is a beveled block 19 whose bevel normally engages the beveled surface of the lever 13 and the upper end of which is engaged by a screw 20 entering an aperture 21 in the upper edge of the blade.

To attach the removable blade to the head 2 the neck 11 is placed between the dovetails 3 and 4 and the head 11 inserted in the cavity between the dovetails and the hatchet-head 2 until the lower end of the head 11 abuts the shoulder 7 as shown in Figs. 1 and 2. The screw 20 is now driven down entirely into the aperture 21 when it will engage the block 19 and force the same against the lever 13 thus driving the latter against the tension of the spring 15 upon the head 2 causing the lug 17 to enter the recess 18 of the said head when the blade will be in operative position. The dovetails 3 and 4 prevent the blade from leaving its position in a forward direction, the lug 17 prevents an upward movement and the shoulder 7 prevents a downward movement of the said blade.

What I claim is:—

A hatchet comprising a handle, a head secured to said handle and formed with a forwardly projected shoulder at its lower termination and with a lug receiving recess, oppositely disposed dovetails projected from the upper termination of the said head and prolonged its entire depth to abut the said shoulder, a detachable blade formed with a neck for insertion between the said dovetails, a head formed with a suitable recess

made integral with the said neck for insertion between the body of the said hatchet-head and the dovetails, a spring actuated lever pivotally disposed within the recessed head, a lug carried by said lever for insertion in the recess in the hatchet-head, a beveled block normally engaging the said lever and a screw for engagement with the said beveled block.

Copies of this patent may be obtained for five cents each, by addressing the "Commissioner of Patents, Washington, D. C."

In testimony that I claim the foregoing 10 as my own I have hereto affixed my signature in the presence of two subscribing witnesses.

OLOF EMANUEL MYREN JOHNSON.
